UNITED STATES PATENT OFFICE.

MARCELLUS R. SHEDD, OF LANCASTER, NEW YORK, ASSIGNOR TO GOULD COUPLER COMPANY, A CORPORATION OF NEW YORK.

ELECTRICAL SYSTEM OF DISTRIBUTION.

1,372,096.

Specification of Letters Patent. Patented Mar. 22, 1921.

Application filed November 23, 1915. Serial No. 63,011.

To all whom it may concern:

Be it known that I, MARCELLUS R. SHEDD, a citizen of the United States, and a resident of Lancaster, county of Erie, State of New York, have invented certain new and useful Improvements in Electrical Systems of Distribution, of which the following is a specification.

My invention relates to electrical systems of distribution and more particularly to improved generator regulation in such systems, where a storage battery is charged by the generator. While useful in other situations my invention is especially applicable in car lighting systems, where the generator is driven at variable speed, as by the car axle. The main object of the invention is to provide improved regulation of the carbon pile type. Further and more specific objects, features and advantages will more clearly appear from the detail description given below, taken in connection with the accompanying sheet of drawings, which forms a part of this specification.

In the drawings Figure 1 illustrates diagrammatically a system embodying my improvements in one form, and Fig. 2 is a similar diagram, illustrating a modified form of system.

Referring to Fig. 1, 1 represents a generator having a shunt field winding 2. 3 represents a storage battery adapted to be connected to the generator 1, to be charged thereby, by the main switch 4, which may be of any suitable form. A lamp circuit 5 is shown connected across the battery through a switch 6. Serially connected between the battery and lamps is a carbon pile 7, the resistance of which is adapted to be varied by a lever 8, controlled by a solenoid 9 connected across the lamp circuit, so that it controls the carbon pile 7 to maintain the voltage on the lamps substantially constant.

10 represents a carbon pile in series with the shunt field 2. Operating on one end of the pile 10 is a lever 11 pivoted at 12 and operating on the other end of the pile 10 is a lever 13 pivoted at 14. The end of the long arm of the lever 13 is provided with a downwardly extending knife edge 15, and also with a pin 16 operating in a slot 17, in the end of the long arm of the lever 11. Adapted to bear upon the knife edge 15 is a member 18 apertured at each

end and through which apertures rods 19 and 20 pass respectively. The rod 19 has a core 21 of a solenoid 22 connected to its lower end, the solenoid coil 22 being connected in the generator circuit between the generator and battery, so as to be responsive to generator current variations. The rod 19 is provided with a pin 23, so that when the solenoid 22 raises the core 21 from its seat, the pin 23 moves member 18 upwardly, which causes the long arms of both levers 11 and 13 to move upwardly, they being connected together by the pin and slot connection 16, 17. This causes the resistance of the pile to be increased from both ends, thereby making the device more sensitive in regulating the generator by variation of the resistance of the pile. The other end of the member 18 is similarly adapted to rest on a pin 24, secured to the rod 20. The rod 20 has connected to its lower end a core 25, adapted to be raised from its seat by a solenoid 26, whose coil is connected across the generator to be responsive to voltage variations across the generator and battery.

In operation the generator when running at sufficient speed will charge the battery and supply the lights. If the current tends to become excessive, the coil 22 will raise the core 21, which will raise the right hand end of member 18. This raises the knife edge 15 on the lever 13, and consequently the long arms of both levers 11 and 13 are raised, thus quickly increasing the resistance in the generator field and decreasing the generator voltage, so as to prevent the current exceeding the desired limit. As the battery becomes charged, its voltage rises and when the voltage has reached the desired value, either that of a substantially fully charged battery or any lesser value, the coil 26 raises its core and causes the other end of member 18 to be raised, thereby tending to increase the resistance of pile 10 and further weaken the generator. This causes it to deliver less current so that coil 22 is no longer able to sustain its core 21, which drops down against its seat. The voltage coil 26, however, continues to act to prevent the generator voltage going materially higher, so that the charging of the battery is tapered off and serious overcharging prevented.

The arrangement shown in Fig. 2 is the

same, except that the coil 22 is shown connected in the battery circuit, so that it is responsive only to battery current changes instead of total generator output, as in Fig. 1.

5 Various modifications and changes may be made without departing from the spirit and scope of the invention. For instance, instead of using a carbon pile composed of a plurality of carbon disks, any other suitable medium may be used whose resistance varies with variations in pressure thereon.

In a copending application filed by me, Serial No. 63012, filed November 23, 1915, I have disclosed the generator regulator herein disclosed and have made claims to it as a regulator, the present application being confined as to its claims to the electrical system herein shown and described.

Having fully and clearly described my improvements, what I claim as new and desire to secure by Letters Patent is:

1. An electrical system of distribution having in combination a generator, a storage battery connected to be charged thereby, a 25 carbon pile regulating the generator, a lever operating on one end of said pile, a lever operating on the other end of said pile, a member the movement of which actuates both of said levers to vary the resistance of 30 said pile, a coil serially connected between the generator and battery, means whereby said coil acts upon said member to actuate said levers, a coil responsive to voltage variations and means whereby said last 35 mentioned coil acts upon said member to actuate both of said levers.

2. An electrical system of distribution having in combination a generator, a storage battery connected to be charged thereby, a 40 carbon pile regulating the generator, a member acting on one end of said pile, a member acting on the other end of said pile, and means comprising a coil responsive to variations in current flowing from the generator 45 to the battery, for causing the actuation of both of said members to vary the resistance of said pile and a voltage coil for causing the actuation of both of said members to vary the resistance of said pile.

50 3. An electrical system of distribution having in combination a generator, a storage battery connected to be charged thereby, a carbon pile regulating the generator, two members acting on said pile to vary the resistance thereof, and means comprising a coil responsive to variations in current flowing from the generator to the battery, for causing the actuation of both of said members to vary the resistance of said pile and 55 a voltage coil for causing the actuation of both of said members to vary the resistance of said pile.

4. An electrical system of distribution

having in combination a generator, a storage battery connected to be charged thereby, a 65 carbon pile regulating the generator, two levers acting on said pile to vary the resistance thereof, a member adapted to actuate both of said levers simultaneously, a coil serially connected between the battery and 70 generator, adapted to move said member when the current therein reaches a predetermined value, a voltage coil adapted to move said member when the voltage thereacross reaches a predetermined value, each of said 75 coils being without substantial effect upon said member when the factor affecting it is below such predetermined value.

5. An electrical system of distribution having in combination a generator, a storage battery connected to be charged thereby, a carbon pile regulating the generator, a lever operating on one end of said pile, a lever operating on the other end of said pile, means whereby movement of one lever causes 85 movement of the other lever, and a member having a voltage controlled magnet operating on one end thereof, and a current controlled magnet operating on the other end thereof, said member being adapted to actuate 90 both of said levers when operated by either of said magnets.

6. An electrical system of distribution having in combination a generator, a storage battery connected to be charged thereby, 95 a carbon pile regulating the generator, a lever operating on one end of said pile, a lever operating on the other end of said pile, means whereby movement of one lever causes movement of the other lever, a member, movement of either end of which is adapted to actuate both of said levers, a current controlled solenoid having a movable core for moving one end of said member and a voltage solenoid having a movable core 105 for moving the other end of said member.

7. An electrical system having in combination a generator, a storage battery connected to be charged thereby, a carbon pile regulating the generator field strength, 110 mechanism operating said pile to vary its resistance, an electromagnet responsive to voltage changes of the system, a current responsive electromagnet connected between the generator and battery, separately movable armatures for said electromagnets, each of said armatures upon being sufficiently attracted by its electromagnet, being adapted to cause the actuation of said mechanism to vary the resistance of said pile at both ends 115 thereof without movement of the other armature.

In testimony whereof I have signed my name to this specification.

MARCELLUS R. SHEDD.
